CROSS PENDANT OR THE LIKE

Robert K. Scott, Jacksonville, Fla., assignor to Abla House, Inc., Jacksonville, Fla.

Filed Nov. 8, 1972, Ser. No. 304,662

Term of patent 14 years

Int. Cl. D11—01

U.S. Cl. D45—16 B

FIG. 1 is a front elevational view of a cross pendant or the like showing my new design; portions of the neck cord being omitted in FIGS. 1-4 for ease of illustration; FIG. 2 is a right side elevational view; FIG. 3 is a rear elevational view; FIG. 4 is a top plan view; and

FIG. 5 is a section on an enlarged scale taken along line 5-5 of FIG. 1, the neck cord being omitted for clarity.

I claim:

The ornamental design for cross pendant or the like, substantially as shown.
